DOWEL LAPING MACHINE

Arthur T. Walker, Berkeley, Calif.

Application November 27, 1933, Serial No. 699,881

3 Claims. (Cl. 51—59)

This invention relates to dowel lapping machines, and has for its principal object the provision of a simple and effective machine for simultaneously lapping a plurality of lengths of doweling so as to make the same perfectly straight, uniform in diameter, and truly round in cross-sectional form in order that the same may be used in the manufacturing of arrow shafts.

In practising the invention, I provide a machine including a pair of reciprocating lapping plates between which lengths of doweling are arranged and supported at an angle to the path of movement of the plates. The plates are reciprocated in opposition to each other and their adjacent lapping surfaces engage the lengths of doweling supported therebetween and create a lapping action, lapping the lengths of doweling so that the same will be perfectly straight, uniform in diameter from end to end, smooth in finish, and truly round in cross-sectional form.

One form which the invention may assume is exemplified in the following description and illustrated by way of example in the accompanying drawing, in which—

Fig. 1 is a view in side elevation of a machine embodying the preferred form of my invention, with parts thereof broken away and in section to illustrate certain details of construction;

Fig. 2 is a plan view of the machine with a portion of the upper lapping plate broken away to disclose the work-holding devices for supporting the doweling between the lapping plates;

Fig. 3 is a view in transverse section taken on line III—III of Fig. 2, looking in the direction of the arrows; and

Figs. 4 and 5 are perspective views of the work-holding members in the relative positions which they assume on the frame between the lapping plates.

Referring more particularly to the accompanying drawing, 10 indicates a machine for lapping lengths of doweling. It is contemplated that the machine be used in the manufacture of arrows and it is well known that straightness, uniformity of diameter, trueness of form, and smoothness of finish are essential requisites of good arrows.

The machine illustrated includes a rigid stationary frame 11, of any suitable construction and which is here illustrated as composed of a horizontal section 12 supported by rigid uprights 14. At one end of the frame, the horizontal section 12 is fitted with bearings 15 rotatably supporting a crank shaft 16 which is arranged transversely of the frame, as illustrated. A pulley 17

is arranged at one side of the frame and is secured on a projecting end of the crank shaft 16. Rotation is imparted to the crank shaft through the medium of this pulley 17, but it is obvious that a driving medium for the crank shaft may be mounted directly on the frame or closely adjacent thereto and directly connected to the crank shaft for operating the same.

The crank shaft 16 is formed with two throws or cranks 18 and 19 which are disposed at 180° apart. At the end of the frame 11 opposite the crank shaft are two longitudinally arranged guide members 20, which are disposed one at each side of the horizontal section 12 of the frame and rigidly secured thereto. Transversely arranged roller shafts 21 are supported at their ends in the guide members 20, and each shaft is fitted with a pair of idler rollers 22. The rollers 22 of each pair are arranged contiguous to the inner sides of the guide members, as illustrated.

Disposed between the guide members 20 and guided thereby for reciprocation longitudinally of the frame 11, above the horizontal section 12 thereof, is a lower lapping plate 23. This lapping plate 23 is supported by the rollers 22 and is freely movable thereover during operation. The lapping plate is, of course, horizontally disposed, as illustrated. For the purpose of reciprocating the lower lapping plate 23, it is connected by means of a connecting rod 24 to the throw or crank 18 of the crank shaft 16.

Overlying the lower lapping plate 23 is a floating upper lapping plate 25, which is also horizontally disposed between the guide members 20 and guided by the latter for reciprocation longitudinally of the frame 11. The upper lapping plate 25 is connected to the throw or crank 19 of the crank shaft 16 by means of a connecting rod 26.

Inasmuch as the throws 18 and 19 of the crank shaft 16 are arranged at 180° apart, the upper and lower lapping plates will reciprocate in opposition to each other. The under surface of the upper lapping plate 25 and the upper surface of the lower lapping plate 23 are abrasive in character, and in the present instance I have illustrated these lapping surfaces of the plates 23 and 25 as formed of sandpaper, or a like substance, extending over the entire lapping area thereof. The lower lapping plate 23 is formed with a number of spaced vertical openings 27 so that dust or cuttings will not accumulate on the lapping surface thereof.

Extending laterally between the guides 20 and interposed between the lapping surfaces of the

plates 23 and 25 is a pair of work-holding members 28. The ends of these members project through openings in the guides 20 and are connected to clips 29 secured at the exterior of the guides. The connection between the work-holding members 28 and the clips 29 is such that the position of the members 28 may be adjusted so that they will accommodate doweling of different lengths for lapping. It will be noticed that the opposite faces of the work-holding members 28 are so formed as to engage the ends of a plurality of lengths of doweling to hold the same at a slight angle to the path of travel on reciprocation of the lapping plates 23 and 25. The work-holding members 28 are less in thickness than the diameter of the doweling and are so positioned that the lengths of doweling supported thereby will be engaged at opposite sides by the lapping surfaces of the plates 23 and 25.

In operation of the device, it is constructed and assembled as illustrated and described. The lengths of doweling to be lapped are then interposed between the lapping surfaces of the plates 23 and 25 and engaged at their ends by the work-holding members 28 to support the lengths of doweling in a position with their axes at an angle to the path of reciprocation of the lapping plates 23 and 25.

A drive is then transmitted to the crank shaft 16 which, through the medium of the connecting rods 24 and 26, will cause the lapping plates 23 and 25 to reciprocate in opposition to each other. This operation of the lapping plates 23 and 25 will create a lapping action on the lengths of doweling interposed between the lapping surfaces thereof. Due to the angular arrangement of the lengths of doweling, the same will revolve so that all surfaces thereof will be exposed to the lapping action. This action is such that the lengths of doweling, when the lapping operation is completed, will be perfectly straight, uniform in diameter, smooth in finish and perfectly round in cross-sectional form.

From the foregoing it is obvious that I have provided a comparatively simple machine which will be inexpensive to construct and operate and which will operate efficiently in lapping simultaneously a considerable number of lengths of doweling so that the same will be perfectly straight, uniform in diameter from end to end, and perfectly round in cross-sectional form.

While I have shown the preferred form of my invention, it is to be understood that various changes may be made in the machine without departing from the invention as defined in the appended claims.

Having described my invention, what I claim and desire to secure by Letters Patent is—

1. A machine for lapping dowels comprising spaced lapping plates mounted for oscillation and work-holding means consisting of stationary bars disposed between the lapping plates to prevent axial movement of dowels placed between the plates, said bars being shaped to hold the dowels at an angle to the direction of oscillation of the plates.

2. In a dowel lapping machine, the combination with spaced oscillating lapping plates of work-holding means comprising stationary bars disposed between the plates, said bars being arranged to engage the ends of a plurality of dowels loosely to permit them to be rotated by the lapping action of the plates and to retain them at an angle to the direction of oscillation of the plates.

3. In a dowel lapping machine, the combination with spaced oscillating lapping plates of work-holding means comprising stationary bars disposed between the plates at right angles to the direction of oscillation of the plates, one of said bars having a central recess to receive the ends of a group of dowels and the other bar having a pair of recesses spaced from its center to receive the opposite ends of said dowels to maintain the dowels in a proper position to be lapped.

ARTHUR T. WALKER.
